CLAIM

The ornamental design for an electromagnetic radiation converter, as shown and described.

DESCRIPTION

FIG. 1 is a top perspective view of an electromagnetic radiation converter showing my new design; FIG. 2 is a bottom perspective view thereof; FIG. 3 is a top plan view thereof; FIG. 4 is a bottom plan view thereof; FIG. 5 is a right side view thereof; FIG. 6 is a left side view thereof; FIG. 7 is a front view thereof; and FIG. 8 is a rear view thereof; and FIG. 9 is a top and bottom plan close-up fragmental view thereof.
